UNITED STATES PATENT OFFICE.

JOSEPH B. HENDRIX AND CLYDE DUROSSETTE, OF WALSENBURG, COLORADO.

GREASE-GUN.

1,190,241.

Specification of Letters Patent.

Patented July 4, 1916.

Application filed April 4, 1914. Serial No. 829,623.

To all whom it may concern:

Be it known that we, JOSEPH B. HENDRIX and CLYDE DUROSSETTE, citizens of the United States, residing at Walsenburg, in the county of Huerfano and State of Colorado, have invented certain new and useful Improvements in Grease-Guns, of which the following is a specification.

Our invention relates to what is commonly termed a "grease gun," that is to say, a form of syringe used for handling oils and grease to enable oil cups and grease cups on machinery to be readily filled.

As its primary object, the invention contemplates a construction of plunger or piston whereby, through longitudinal movement of said piston in one direction, the oil or grease is automatically transferred from one to the other side thereof, and, upon a reverse movement, is forcibly fed to any one of a plurality of barrel or cylinder outlets.

A further object of the invention resides in the provision of an actuating element so associated with the barrel or cylinder piston as to impart longitudinal movement thereto independent of a like movement on the part of said element.

A further object of the invention is to enable heavy lubricants to be quickly handled with the grease gun and to avoid the difficulty heretofore experienced in filling the grease gun with the grease.

The invention, as a still further object, aims to provide an improved grease gun wherein air under pressure may be utilized, if desired, to actuate the cylinder piston, the actuating element above noted, when thus operated, being first detached or rendered inoperative.

The above and additional objects are accomplished by such means as are illustrated in their preferred embodiment in the accompanying drawings, described in the following specification and then more particularly pointed out in the claims which are appended hereto and form a part of this application.

In describing our invention in detail reference will be had to the accompanying drawings wherein like characters denote like or corresponding parts throughout the several views, and in which:—

Figure 1 is an elevation of an oiler or grease gun constructed in accordance with

the present invention; Fig. 2 is a section on the line 2—2 of Fig. 1; Fig. 3 is a section on the line 3—3 of Fig. 2; and Fig. 4 is a top plan view.

Referring now to the drawings by numerals, 1 designates as an entirety the cylinder or barrel into which the grease or oil acted upon is poured. Caps 2 and 3 are threaded respectively to the cylinder 1 at the top and bottom thereof, the former, 2, having a central opening 4 through which a sleeve like operating element 5 extends, said element being annularly enlarged as indicated at 6 to prevent, as is apparent upon reference to Fig. 2 of the drawings, longitudinal bodily movement of the said sleeve independent of the cap. The bore of said sleeve 5 is threaded to receive a hollow or sleeve like operating screw 7, which screw, upon a turning of the element 5, is either bodily raised or lowered. Arms or handles 8 radiate from the periphery of the said element 5 to facilitate operation of the device by hand.

Within the bore of the operating screw 7, and extending throughout the length of the said screw, is the rod 9 of a plunger or piston 10. Rod 9 is preferably swiveled on the piston 10 so that it can rotate relatively thereto. In the operation of the device by hand, the said rod 9 is made rigid with the operating screw 7 through the medium of a cotter pin 11 extending therethrough, from which arrangement, it is apparent that the plunger 10 will be reciprocated or made to move longitudinally within the cylinder upon a turning of the operating element 5. Said plunger or piston 10 is provided with ports 12, said ports being normally closed, by means of a valve member 13 in the nature of a flat plate like spring arranged over the piston rod 9 and against the under face of the piston.

A removable plug 14 is provided to permit, when removed, a filling of the cylinder with oil or grease. Valve controlled outlets 15, 16 and 17 are arranged respectively adjacent the top, bottom and middle of the cylinder, any one of which is adapted to receive a flexible hose section 18 through the medium of which the oil or grease acted upon is conveyed to the grease or oil cup to be filled upon operation of the plunger or piston 10. As a means whereby a turning of the plunger 10 is prevented, I provide an ex-

tension 19 integral with the plunger and working within a longitudinal groove 20 of the cylinder, said groove being open to the interior of the cylinder as indicated in Fig. 5 3 of the drawings.

Operation by hand is as follows: Plunger or piston 10 is moved, by a turning of the element 5, to its lowermost position or to the position indicated in Fig. 2. Plug 10 14 is then removed and the cylinder or barrel filled. The several outlets being closed, the element 5 is turned and, being incapable of longitudinal movement, such movement is imparted to the operating screw 7. Said 15 screw 7 being rigid with piston rod 9, it is apparent that the piston or plunger 10 will be made to move longitudinally of the cylinder. As the oil or grease is compressed, the valve member 13 is forced from engagement 20 with piston 10 to open ports 12, thereby permitting, upon continued operation of the element 5, the automatic transfer of the oil or grease within the cylinder from one to the other side of the piston. When transferred, 25 the valve of the middle outlet 17 is opened, and, as said valve has attached thereto the flexible hose section 18, it is evident that upon a reverse turning of the element 5 (valve in outlet passage 16 being closed) the 30 oil or grease within the barrel is forced, by movement of the piston, through the said outlet to the oil cup or grease cup in connection with which the device is used. The plunger having been moved to close outlet 35 17, the hose section 18 is detached therefrom and attached to outlet 16 at the bottom of the cylinder, in which event, continued movement of the said plunger will provide for a continued feeding of the oil or grease in the 40 desired manner.

When it is desired that air under pressure be used to actuate the plunger 10, the cotter pin 11 is removed after the cylinder has been filled in the manner described above, the element 45 5 rotated until operating screw 7 is in its uppermost position, such movement being effected without a like movement on the part of either the rod 9 or piston. Air under pressure is then admitted to the cylinder by way of outlet 16, which air being directed against the valve member 13 and the 50 under side of the plunger will cause the latter to move upwardly to forcibly feed the oil or grease in the desired manner by way of 55 either outlet 17 or outlet 15, the hose section 18 being of course attached thereto. The rods 7 and 9 are connected by the cotter pin

11 and the piston is lowered and the cylinder is again filled in the manner described above, when the operation of forcing the 60 grease out by fluid pressure can be repeated.

In reduction to practice, we have found that the form of our invention, illustrated in the drawings and referred to in the above description, as the preferred embodiment, is 65 the most efficient and practical; yet realizing that the conditions concurrent with the adoption of our device will necessarily vary, we desire to emphasize the fact that various minor changes in details of construction, 70 proportion and arrangement of parts may be resorted to, when required, without sacrificing any of the advantages of our invention, as defined in the appended claims.

Having thus fully described our invention, what we claim as new and desire to secure by Letters Patent, is:—

1. In a grease gun, a cylinder, a sleeve-like operating element mounted for rotation within an opening of said cylinder, said element being immovable longitudinally independent of said cylinder, a hollow sleeve-like operating screw, said screw being movable longitudinally of said cylinder, a piston, a piston rod fastened to said piston, said rod 85 being rigid with said screw whereby to impart movement to said piston through rotation of said operating element.

2. In a grease gun, a cylinder, a rotatable sleeve-like operating element immovable longitudinally with respect to said cylinder, the bore of said element being interiorly threaded, an operating screw extending through the bore of said element, said screw being movable longitudinally through rotation of 95 said element, a piston, and a piston rod fastened to said piston and adapted to be detachably connected to said operating screw whereby to move said piston by a rotation of said element.

3. In a grease gun, a cylinder, a piston, a piston rod, a hollow screw rod embracing said piston rod and having detachable connection therewith for the purpose specified, and means engaging the said hollow rod to 105 rotate it.

In testimony whereof we affix our signatures in presence of two witnesses.

JOSEPH B. HENDRIX.
CLYDE DUROSSETTE.
